UNITED STATES PATENT OFFICE.

ISAAC HENRY LEITER, OF NEW YORK, N. Y.

DESIGN FOR FURNITURE-GIMP.

SPECIFICATION forming part of Design No. 34,851, dated July 23, 1901.

Application filed June 17, 1901. Serial No. 64,958. Term of patent 14 years.

To all whom it may concern:

Be it known that I, ISAAC HENRY LEITER, a citizen of the United States, residing in the city, county, and State of New York, have invented and produced a new and original Design for Furniture-Gimp, of which the following is a specification, reference being had to the accompanying drawings, forming a part thereof.

Figure 1 is a front view of a portion of gimp made according to my new design shown upon an enlarged scale; Fig. 2, a rear view of the same.

As shown in the drawings, the leading or material feature of my design consists of the raised central band *a*, formed of three longi-

tudinal lines of diagonal cross-braids *a' a² a³*, crossed at equal distances by the transverse bars *b*, said raised central band *a* being flanked on either side by a fringe of loops *c*, as shown 20 in Fig. 1. The back of the gimp is flat and shows mainly the cross-strands, of which the loops *c* form the bights.

Having described my invention, what I claim as new, and desire to secure by Letters 25 Patent, is—

The design for furniture-gimp herein shown and described.

ISAAC HENRY LEITER.
